UNITED STATES PATENT OFFICE.

WILLIAM TRACY, OF POUGHKEEPSIE, NEW YORK, ASSIGNOR TO LANDERS, FRARY & CLARK, OF NEW BRITAIN, CONNECTICUT.

KNIFE FOR CUTTING OFF BANANAS.

SPECIFICATION forming part of Letters Patent No. 242,237, dated May 31, 1881.

Application filed March 21, 1881. (Model.)

To all whom it may concern:

Be it known that I, WILLIAM TRACY, of Poughkeepsie, in the State of New York, have invented a new Improvement in Knives for 5 Fruit-Picking; and I do hereby declare the following, when taken in connection with the accompanying drawings and the letters of reference marked thereon, to be a full, clear, and exact description of the same, and which said drawings constitute part of this specification, and represent, in—

Figure 1, a view from one side; Fig. 2, the reverse side.

This invention relates to an improvement in 15 knives for cutting fruit from the stem, with special reference to cutting bananas from their stem.

Bananas as they come to market are in an unripe condition, some ripening much quicker 20 than others. In the sale of this article it is necessary to cut from the stem only the ripe ones; but they are so close together and are so compact that it is difficult to separate any particular one from the stem without injuring others, 25 as the blade of the knife generally used is liable to slip and gash the adjacent fruit. So, also, in cutting parts of bunches of grapes a similar difficulty is experienced.

The object of this invention is the construction 30 of a cutter which may be used with facility without danger to the adjacent fruit; and the invention consists in the construction of a knife as hereinafter described, and particularly recited in the claim.

35 A is the blade, made as narrow as convenient with due regard to strength, and extending from a shank, B. Toward the end the blade is curved, giving to the cutting-edge a semi-hook shape, so that a person holding the

knife by the handle C may pass the curve in 40 around the stem, and then, by an outward pull, cut the stem without danger of injuring the adjacent fruit, as is the case in the common knife and such as generally used.

In some cases a pushing cut is desirable; 45 and in order to adapt the knife for such a cut and give to it the advantage of a drawing cut as well as a pushing cut, I make upon the back of the blade, and distant from the point opposite the curved edge, as at b, a sharp edge diagonal to the handle. The back of the blade from the sharp edge to the point, as also the back from the other end of the sharp edge, 50 serve as guards to prevent cutting adjacent fruit, and so that a direct push upon the blade 55 gives a shear or drawing cut.

While I prefer to make the sharp back b in a straight line diagonal, it may be somewhat curved and attain the object of a diagonal cut—that is, the drawing cut. I therefore do not 60 wish to be understood as limiting this invention to a straight diagonal edge; but by the term "diagonal" I wish to be understood as embracing a line of edge not parallel with the line of the handle. 65

I claim—

The herein-described knife, consisting of the blade constructed with a semi-hooked cutting-edge, and with the diagonal cut upon the back of the curved portion of the blade and distant 70 from the point, so that the back forms a guard between the cutting-edge and point, substantially as described.

WILLIAM TRACY.
